(57) **CLAIM**

The ornamental design for a cable tie as shown and described.

DESCRIPTION

FIG. 1 is a front perspective view of the cable tie;

FIG. 2 is a rear perspective view thereof;

FIG. 3 is a front elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is an enlarged view of the right side elevation view thereof;

FIG. 9 is an enlarged view of the left side elevation view thereof;

FIG. 10 is an enlarged view of portion 10-10 of FIG. 1 thereof;

FIG. 11 is an enlarged view of portion 11-11 of FIG. 2 thereof;

FIG. 12 is an enlarged view of portion 12-12 of FIG. 3 thereof; and,

FIG. 13 is an enlarged view of portion 13-13 of FIG. 6 thereof.

The evenly spaced broken lines depict portions of the cable tie that form no part of the claimed design. The dash-dot-dash broken lines depict the boundaries of the claim and form no part thereof.

1 Claim, 5 Drawing Sheets
